UNITED STATES PATENT OFFICE.

ANTHONY FRICKER, OF LAKewood, OHIO.

CLASP.

Application filed April 28, 1923. Serial No. 635,290.

This invention relates to clasp structures and more particularly, to such devices for holding in a substantially upright or vertical position either one or a plurality of paper 5 sheets, files or the like, up to thicknesses of an inch or so. The present application is a continuation in part of my prior patent for clasps, dated May 6, 1924, No. 1,493,072.

The object of the present invention is to 10 provide an improved device of the class described having a base of simple and inexpensive form for detachably receiving and holding in a substantially upright position a clasp corresponding substantially to that shown in 15 my prior patent before referred to, said clasp being merely provided with a plurality of easily and inexpensively formed openings which cooperate with projections of the base to provide a firm but detachable locking connection therebetween. The detachable connection of the clasp and base not only enables 20 them to be shipped, stored and sold separately, but also enables the clasp to be used independently of the base whenever desired. 25 Further objects of the invention are in part obvious and in part will appear more in detail hereinafter.

In the drawing, which represents one suitable embodiment of the invention, Fig. 1 is 30 a perspective view of my improved device; Fig. 2 is a detailed sectional view taken on the line 2—2, Fig. 4; Fig. 3 is a similar view taken on the line 3—3, Fig. 4; Fig. 4 is a plan view of the base; Fig. 5 is a detail elevation of the head or eye of my improved 35 clasp; and Fig. 6 is a detail edge view thereof.

Referring to the drawing, my improved clasp, which forms the subject matter of the prior patent before referred to, is made from 40 a single strip of steel of any suitable width and length, one satisfactory size of clasp being about three-fourths of an inch wide and approximately six inches long. The head of the clasp, indicated generally at 1, is in the 45 form of a loop or eye joining the two arms 2, which lie parallel and in contact over an appreciable portion of their length, due to the formation of the clasp in a manner to impart inherent tension thereto, such that the normal 50 position of the arms, if they could pass each other, would be at approximately right angles to each other. This effect is secured

in the present clasp by forming the eye 1 with two side bends 3 and an end bend 4, said bends being put in the metal of the tempered strip 55 so that subsequent tempering is unnecessary.

The side and end bends 3, 4 are formed in a manner to over-bend the material, or in other words, to put into the clasp more initial tension than is necessary, after which, one or 60 more of the bends are straightened to take out a part of the tension and leave just the amount necessary to give the arms sufficient resiliency and holding ability and also keep them parallel in the various positions of the 65 clasp up to full open position with the arms about an inch apart.

One of the arms 2 of the clasp is longer than the other, say approximately an inch longer, and the end of the shorter arm is flared outwardly, as at 5, so as to form a mouth adapted 70 to readily receive the edges of the sheets of paper or the like inserted in the clasp.

The base of my improved device may be 75 of any suitable shape or design, and of any suitable material, so long as it is of sufficient depth to receive the eye of the clasp and of sufficient area and weight to provide a substantial support for the clasp when holding a mass of papers or the like in a substantially 80 upright position. In the present embodiment, said base is made of pressed metal in substantially inverted saucer shape, as clearly indicated in Figs. 3 and 4. Said base, indicated generally at 6, is formed with a circular, substantially flat top portion 7, in the center of which is a substantially rectangular opening or cut out portion 8, of such size and shape as to snugly receive the eye 1 of the 85 clasp, as clearly indicated in Figs. 2 and 3. 90

In forming said opening, a portion of the metal of this part of the top portion 7 is bent or turned down at the sides 9 of the opening so as to provide two opposed, depending integral ears 10. Said ears are of substantially 95 semi-circular form to correspond to the shape of the edges of the clasp eye, which edges are engaged by the ears when the device is assembled, said ears assisting the locking connections, now to be described, in holding the 100 clasp in a substantially rigid, upright position.

Said ears, which at their junction or merger with the top portion 7 are narrower

than the opening between sides 11 of opening 8, are bent or turned down so as to leave in each corner of the opening a portion of the metal of the top portion 7, as clearly indicated in Fig. 4, thereby providing four projections 13 which are adapted to co-operate with suitable openings, or, as illustrated, notches 14 in the material forming the eye of the clasp to provide a firm but detachable locking connection between the base and clasp. The notches 14 of the eye of the clasp are cut in the edges of the strip at the side bends 3, there being two recesses at each side bend, as clearly indicated in Figs. 5 and 6.

15 The device is assembled by passing the arms 2 of the clasp up through opening 8 until the side bends 3 of the clasp eye are reached, whereupon the corner projections 13 of the base will enter the recesses 14 of 20 the clasp, and thereby firmly but detachably lock the clasp and base together with the arms 2 of the clasp extending in a substantially upright position, or if the base is not in a horizontal position, the arms will extend in a position substantially normal thereto. When it is desired to detach the clasp, so as to use it independently, or for other reasons, the portions of the clasp just above the side bends 3 are pressed inwardly, so as 30 to disengage the projections and recesses, whereupon the arms of the clasp may be readily withdrawn through opening 8 of the base.

Having described my invention, I claim:

1. A device of the class described, comprising a spring metal clasp having an eye and two arms, the material of said eye being provided with an opening, and a base having an opening to receive the clasp eye to hold the arms thereof outstanding therefrom, 35 said base being provided with a projection adapted to enter the opening of the clasp eye to maintain the parts in assembled relation, said base being also provided at the sides of said opening with ears adapted to 40 engage the edges of said clasp eye, whereby said clasp will be firmly held in said relation.

2. A device of the class described, comprising a spring metal clasp having an eye and two arms, the material of said eye being 50 provided on opposite sides with notches, and a base having a substantially rectangular opening to receive the clasp eye to hold the clasp arms in a position outstanding from the base, said base being provided in opposite corners of said opening with projections adapted to enter said notches, whereby the clasp and base will be firmly secured together.

3. A device of the character described comprising a spring metal clasp having an eye 60 and two arms, the material of said eye being provided with an opening, and a base having an opening to receive the clasp eye to hold the clasp arms in a position outstanding from the base, said base being provided with 65 a projection adapted to enter said opening

of the clasp eye, whereby the clasp and the base will be firmly secured together, said base being also provided at one side of said opening with an ear adapted to engage said clasp eye, thereby assisting in maintaining the 70 clasp arm in said outstanding position, the formation of said ear providing the projection of the base.

4. A device of the class described, comprising a clasp of resilient material formed with an eye and two arms and adapted for independent use, and a base having an opening to receive the clasp eye and confine said clasp with its arms outstanding therefrom, 75 said clasp and base having portions adapted for interlocking engagement to maintain said described assembled relation, the resiliency of the material forming the eye permitting separation of the clasp from the base by pressing the material of said clasp eye inwardly just 80 above the base.

5. A device of the class described, comprising a clasp of flat resilient material formed with an eye and two arms and adapted for independent use, and a base having a generally 90 rectangular opening adapted to receive the eye of the clasp and confine said clasp with its arms outstanding therefrom, the material of said clasp eye having an opening, and said base having a projection in its opening adapted for interlocking engagement with said clasp eye opening to maintain said described assembled relation, the resiliency of the material forming the eye permitting separation 95 of the clasp from the base by pressing the material of said clasp eye inwardly just above the base.

6. A device of the class described, comprising a clasp of resilient material formed with an eye and two arms and adapted for independent use, and a base having an opening adapted to receive the eye of the clasp and confine said clasp with its arms outstanding therefrom, the material of said clasp eye having openings on opposite sides, and said base 100 having corresponding projections in its opening adapted for interlocking engagement with said clasp eye openings to maintain said described assembled relation, the resiliency of the material forming the eye permitting separation of the clasp from the base by pressing the material of said clasp eye inwardly just 105 above the base.

7. A device of the class described, comprising a clasp of resilient material formed with an eye and two arms and adapted for independent use, and a sheet metal base having a clasp eye receiving opening the sides of which are adapted to be resiliently engaged by the clasp eye, and ears at the sides of said opening adapted to laterally confine the clasp in a plane therebetween.

8. A device of the class described, comprising a clasp of resilient material formed with an eye and two arms and adapted for inde- 120 125 130

pendent use, and a sheet metal base having a clasp eye receiving opening adapted to confine said clasp with its arms outstanding therefrom, said clasp and base having portions adapted for interlocking engagement to maintain said described assembled relation and adapted for disengagement by springing

said clasp eye to allow disassembly of said clasp and base and ears at the sides of said opening and adapted to abut said eye to assist 10 in maintaining said relation.

In testimony whereof I hereby affix my signature.

ANTHONY FRICKER.
